US00D737313S

(12) **United States Design Patent**
Kim et al.

(10) **Patent No.:** US D737,313 S
(45) **Date of Patent:** ** Aug. 25, 2015

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Sun-Ae Kim**, Seoul (KR); **Mi-Sun Jin**,
Seoul (KR); **Tae-Yeon Kim**, Seoul (KR)

(73) Assignee: **SAMSUNG ELECTRONICS CO.,
LTD. (KR)**

(**) Term: **14 Years**

(21) Appl. No.: **29/461,136**

(22) Filed: **Jul. 18, 2013**

(30) **Foreign Application Priority Data**

Jan. 18, 2013 (KR) 30-2013-0003107

CLAIM

We claim, the ornamental design for a display screen or portion thereof with graphical user interface, as shown and described.

DESCRIPTION

The FIGURE is a front view of a display screen or portion thereof with graphical user interface, showing our new design in an exemplary embodiment.

The broken lines illustrating portions of the display screen or portion thereof with graphical user interface are for environmental purposes only and form no part of the claimed design.
